CONTAINER AND METHOD OF FORMING
RIMS THEREFORChester M. MacChesney, Chicago, Ill., assignor to
Acme Steel Company, Chicago, Ill., a corpora-
tion of Illinois

Application August 2, 1929, Serial No. 382,925

11 Claims. (Cl. 153—1)

This invention relates to an improved method of forming sheet metal rims and bands for use on butter tubs and other containers and to an improved container embodying the use of an improved form of band.

It has heretofore been the practice to form metallic rims for butter tubs and the like by passing a sheet metal band through a number of pairs of rolls or the like by which a transverse flange is first imparted to the sheet metal band and then this transverse flange is subsequently corrugated by the action of a succeeding pair of rolls, thereby providing a transverse flange adapted to compensate for the bending of the band into circular form, since the corrugations adjust themselves to the decreasing circumference of the inner portion of the transverse flange during the bending of the band. While this method of forming bands or rims has been satisfactory in many respects, the bands of this character must be completely formed before application to the tub or other container to be reinforced by them and the successive operations which have been performed to form the flanges on the band and then corrugate them have involved considerable expense. As a part of the present invention, it has been discovered that the operations of the prior practice may be avoided and a band provided which may be applied to a tub or other container prior to the bending of parts thereof into position to form transverse corrugated flanges, thus greatly reducing the cost and permitting the application of corrugated bands to a variety of uses heretofore impossible with bands having pre-formed transverse flanges.

The principal object of the invention is to provide an improved method of forming sheet metal rims or bands to permit the formation of transverse flanges thereon after they have been applied to containers. A further object of the invention is to provide an improved method of forming an annular sheet metal band having parts thereof capable of being bent transversely to form annular flanges without causing the buckling or overlapping of those portions of the metal of the band which form the transverse flanges. A further object of the invention is to provide a butter tub or other container comprising a vessel and a cover secured together by a band having parts thereof bent inwardly to form flanges which engage recesses or shoulders on the vessel and the cover. Another object of the invention is to provide an improved sheet metal band having one or more series of corrugations formed therein

parts thereof bent inwardly to form flanges which versely. Other objects relate to various features of construction and arrangement and to details of the method which will appear more fully hereinafter.

The nature of the invention will be understood from the following specification taken with the accompanying drawings, in which one example of the improved method is explained in connection with several embodiments of the improved band and container.

In the drawings,

Fig. 1 shows a perspective view of a plain sheet metal strip or band employed in forming the improved band or rim of the present invention;

Fig. 2 is a perspective view of the band illustrated in Fig. 1 after it has been provided with two series of corrugations along its longitudinal edges to permit the subsequent transverse bending of these parts of the band to form transverse flanges;

Fig. 3 is a perspective view of an annular rim or band adapted to be applied to a butter tub or the like for securing a cover thereto;

Fig. 4 shows a sectional view through the upper part of a butter tub, showing the application thereto of the band illustrated in Fig. 1 to receive a cover;

Fig. 5 is a sectional view similar to that of Fig. 4 taken on the line 5—5 of Fig. 6, showing the arrangement of the band after the upper series of corrugations thereon have been bent inwardly to form a transverse flange engaging a recess in the cover;

Fig. 6 is a perspective view of a butter tub embodying the features of the present invention and showing the arrangement of the parts after the band illustrated in Fig. 3 has been applied to the tub to hold the cover in position thereon;

Fig. 7 is a perspective view of a portion of a modified form of rim having a series of corrugations along one edge thereof to permit the subsequent bending of this part of the band to form a flange adapted to interlock with a tub cover or the like;

Fig. 8 is a sectional view through the upper part of a tub and a portion of its cover, illustrating the use of the band illustrated in Fig. 7 in forming a rim for the cover adapted to extend downwardly about the upper part of the tub;

Fig. 9 is a perspective view showing another form of the improved metallic band with two series

of corrugations which have been bent transversely, after the completion of the band, to form two rightangularly disposed flanges, and

Fig. 10 is a vertical section through the upper 5 part of a tub and its cover illustrating the use of the band shown in Fig. 9 to form a rim interlocking with a recess in the cover.

In Fig. 1 of the drawings, there is illustrated 10 a portion of a comparatively long and narrow sheet metal band 15 which is adapted to be operated upon to form a reenforcing rim or band for application to a tub or other container. In the practice of this invention, the band 15 is passed through suitable corrugated rolls to impart to the band two series of corrugations 15^a and 15^b which 15 extend along the opposite longitudinal edges thereof, leaving an intervening plain portion 15^c which is free of corrugations. The corrugated band thus formed may be carried in stock in long lengths and cut up to suit its application to 20 a variety of uses according to which the corrugated portions of the band are bent transversely to the body portion 15^c to form parts which are adapted to overlie or interlock with suitable parts 25 of containers and their covers for securing them together. During the formation of the corrugations, the metal of the band is stretched to compensate for the increased length of metal which enters into the corrugations and it has been found 30 that upon subsequently bending these corrugated portions at an angle to the body portion 15^c, the angularity of adjacent corrugations permits them to adjust themselves to transverse bending, even when the band is in circular form, due to the 35 contraction of the corrugations.

One important adaptation of the improved band 40 illustrated in Fig. 2 is illustrated in Figs. 4, 5 and 6, where the band is employed for securing a butter tub and its cover in assembled relation. In forming this improved tub, a suitable length of the band shown in Fig. 2 is bent into circular form and the overlapping ends of the band are then secured together by spot welding or rivets, as shown at 16, thus forming an annular rim 17. 45 The portion of the band forming the series of corrugations 15^a is bent transversely to form a flange 18 and this bending of the corrugated portion of the band may be performed after the formation of the annular rim 17, and the corrugations 15^a then contract sufficiently to allow for the reduction in the diameter of the inner portions of the 50 transversely bent flange. Having formed the rim 17 as shown in Fig. 3, it is applied to the butter tub 19, shown in Fig. 6, made up of a plurality of upwardly extending staves 20 secured together by 55 annular bands or hoops 21 which are formed preferably of sheet metal and provided with beads 21^a along their edges. The outer downwardly tapered wall of the tub is provided adjacent its upper edge with an annular groove or recess 22 which is undercut to form an annular horizontal shoulder 22^a, as shown particularly in Figs. 4 and 5. The rim 17 in the form shown in Fig. 3, is applied 60 to the tub by passing the inwardly directed flange 18 into engagement with the annular groove or recess 22, and this is accomplished by compressing the upper part of the tub sufficiently to permit the band to be passed over the tub until the flange 18 snaps into the recess 22. The rim 65 17 may preferably be passed upwardly from the bottom of the tub over the tapered wall thereof until the flange 18 is opposite the recess but this may be accomplished by compressing the upper 70 part of the tub sufficiently to permit the rim to

be moved downwardly from above and, with either method of application, the compressive force is released from the tub when the band is in proper position to permit the flange 18 to engage the recess 22, whereupon the rim is securely fastened to the tub and projects upwardly therefrom to receive the wooden cover 24 which is illustrated in dotted lines at 24^a in Fig. 4. The cover is then placed in position on the upper end of the tub and the uppermost series of corrugations 15^b, 10 which have retained their initial arrangement in the plane of the body portion 15^c of the band, are then bent transversely to form an inwardly extending flange 25 which overlies the top surface of the cover and which preferably engages a recess 15 24^b formed around the edge of the cover, as illustrated in Fig. 5. The completed band, as thus applied to the tub and its cover, is illustrated in Fig. 6, where the two flanges 18 and 25 formed on the rim engage the annular shoulders on the 20 tub and the cover to hold them firmly in assembled relation. By the provision of the series of corrugations in the band 15, it is possible for the tub 19 to be supplied to the users or consumers with the rim 17 applied thereto, as illustrated in Fig. 4, and then, after the tub has been filled with the commodity to be shipped therein, the cover may be readily put in place and the upper series of corrugations of the band may be bent over the cover by a manual operation and the corrugations then adjust themselves to the transverse arrangement without causing any buckling or deformation of the metal of the band. 25

The improved method of forming the reenforcing rim or band, as described herein, is capable of application to other uses and to other forms of tubs or containers, among which is that illustrated in Figs. 7 and 8, where the band 26 is shown as being formed initially with a series of transverse corrugations 26^a along one edge thereof and a bead 26^b along the other edge thereof, with the intermediate portion 26^c of the band free of corrugations or other irregularities. After the band 26 has been formed as an annular rim 27, the corrugated portion 26^a may be 30 bent transversely to form an angular flange 28, as shown in Fig. 8, adapted to engage a butter tub cover 29 seated on a tub 30. The cover 29 is provided with an annular groove 29^a bounded on its lower side by an outwardly and downwardly inclined annular surface 29^b and bounded on its upper side by an annular projection or shoulder 29^c. The flange 28 seats on the inclined surface 29^b and extends into the recess 29^a beneath the shoulder 29^c, while the body portion 35 of the band or rim extends downwardly around the tub 30 and may be secured thereto by nails or other suitable fastening means. 40

In Figs. 9 and 10 there is illustrated another application of the present invention according 45 to which the sheet metal band 31 is initially provided with two series of corrugations 31^a and 31^b located along one edge of the band but separated from each other by an uncorrugated division line 31^c. After the complete circular band has been 50 formed, the corrugated parts 31^a and 31^b may be bent transversely, as shown in Fig. 9, thus forming a flange 32 extending inwardly from the body portion 33 of the rim, and another flange 34 55 extending downwardly from the flange 32. This form of rim may then be applied to the butter tub 35 and its cover 36, as shown in Fig. 10, where the annular downwardly extending flange 34 is shown engaging an annular downwardly extending recess 36^a formed in the cover in- 60

wardly from its outer edge, while the horizontal flange 32 overlies the top surface or shoulder 36^b of the cover which is formed outwardly of the recess 36^a and preferably below the level of the 5 upper surface 36^c of the cover. The body portion of the band extends downwardly around the upper part of the tub 35 and may be secured thereto by nails or other fastening devices.

Although certain examples of the improved 10 method have been set forth by way of illustration and certain embodiments of the improved rims and containers have been illustrated and described, it will be understood that the method may be practiced in various ways and that the 15 invention may be embodied in various forms within the scope of the appended claims.

I claim:

1. A container comprising a vessel member and a cover member each having an annular shoulder, and a rim having a transverse flange engaging the shoulder on one of said members and a corrugated portion adapted to be bent transversely into engagement with the shoulder on the other of said members.

2. A container comprising a vessel member and a cover member each having an annular shoulder, and an annular metallic rim having a transverse flange engaging one of said shoulders and having a second transverse flange formed by bending a transversely corrugated portion thereof into engagement with a shoulder on the other of said members.

3. A container comprising a vessel member and a cover member, one of said members having an annular shoulder, and an annular metallic rim secured to the other of said members and having an annular series of corrugations adapted to be bent transversely to the body portion thereof into engagement with said shoulder on the other of said members.

4. A container comprising a vessel member and a cover member provided with annular shoulders, and an annular metallic rim comprising a plurality of series of transverse corrugations adapted to be bent transversely to form transverse flanges engaging said shoulders on said members.

5. A container comprising a vessel having an annular recess therein, a cover mounted on said vessel, and an annular metallic band having an inwardly extending flange engaging said recess and having an upwardly extending transversely corrugated part adapted to be bent inwardly over said cover.

6. A container comprising a vessel having an outwardly extending shoulder formed thereon adjacent its upper end, a cover seated on the

upper end of said vessel, and an annular metallic band extending around said cover and the upper part of said vessel and having two inwardly extending transversely corrugated flanges, one of said flanges engaging said shoulder and the other of said flanges engaging the upper side of said cover. 5

7. The method of forming a rim which consists in providing a metal band with a strip of transverse corrugations, then securing the ends of 10 the band to form an annular rim, and then bending the corrugated portion of the band transversely to the body portion thereof to form a transverse flange.

8. The method of forming a rim which consists in providing a metallic band with a plurality of strips of transverse corrugations, then securing the ends of the band to form an annular rim, and then bending said strips of corrugations 20 transversely to the body of the band to form transverse flanges.

9. The method of closing a container which consists in securing to the container an annular metallic band having an annular series of upwardly extending corrugations along its upper 25 edge, placing a cover on said container within said band, and then bending the corrugated portion of said band inwardly over said cover.

10. The method of closing a container which consists in providing a vessel with an annular 30 recess in its outer surface, mounting on said vessel an annular metallic band having an inwardly extending transversely corrugated flange engaging said recess and having an upwardly extending transversely corrugated part located 35 above said vessel, placing a cover on said vessel within said band, and then bending said corrugated part of said band over said cover to form a transverse flange.

11. The method of closing a container which 40 consists in providing a wooden tub with an annular recess in its outer wall, then compressing the tub adjacent said recess and placing in position thereover a completed annular metallic band having an inwardly extending flange 45 adapted to engage said recess when the compressed portion of said vessel is subsequently released and having along its upper edge an annular series of transverse corrugations located above the upper edge of said vessel, then relieving the 50 compression of said vessel, then placing a cover on said vessel within said band, and then turning the corrugated upper edge of said band inwardly over the outer edge of said cover. 55

CHESTER M. MACCHESNEY.
